WEATHER STRIP FOR BOTTOMS OF DOORS AND INSWINGING WINDOWS

Filed March 2, 1929

FIG. 1.

FIG. 3.

FIG. 2.

FIG. 4.

UNITED STATES PATENT OFFICE

CHARLES F. MYERS, OF OKLAHOMA CITY, OKLAHOMA

WEATHER STRIP FOR BOTTOMS OF DOORS AND INSWINGING WINDOWS

Application filed March 2, 1929. Serial No. 344,074.

My invention relates to improvements in weather strip for inswinging doors and casement windows.

The object of my invention is to produce a device of the class which will be new, novel, practical, useful and of utility; which will prevent rain, dust, snow, dirt and the like from passing in or out beneath the door or inswinging casement window of a building and yet permit the opening and closing thereof; which will function on the outside of the opening; which will function without a threshold; which will not mar the floor or floor covering of a building; which will be simple and durable; which may be installed economically; the cost and manufacture of which will be comparatively cheap; which may be easily and quickly installed; which will be efficient in accomplishing all of the purposes and uses for which it is intended.

At the present time there are many kinds of weather strips in use, some of which will function properly around the opening of a sliding window or door, or upon the sides of a swinging door or window, but none of which function properly when installed at the bottom of an inswinging door or window. The most common type of weather strip, for use on the bottoms of inswinging doors and windows, is a strip made usually of brass, or zinc which is so bent that it engages with the threshold of an opening and through the spring of the metal, closes the crack desired. The length of service of this strip is short. It becomes buckled, and in a short time is engaging only a portion of the threshold. This allows leakage. When buckled, it usually scars the floor or floor covering. I believe that at this time there are no means being used or useable for the purpose for which my invention is intended, which has not proven unsuccessful.

My invention obviates and removes all of the objections and deficiencies of the present methods of weather stripping the bottoms of inswinging doors or windows.

With these and other objects in view, as will more fully appear my invention consists in the construction, novel features, and combination of parts hereinafter more fully de-

scribed, pointed out in the claims hereto appended, and illustrated in the accompanying one-sheet drawing, of which,

Figure 1 is an elevational view of a standard inswinging closed door showing my invention installed upon the outside thereof; Fig. 2 is a fragmentary perspective view of my invention showing its position when door is open; Fig. 3 is a sectional view through spring housing showing relation of my weatherstrip to door and threshold; Fig. 4 is a fragmentary perspective view of the door casing and threshold showing the corner plate in position to be used at the end of weatherstrip and abutting plate in position to be used at the meeting of double doors; Fig. 5 is a sectional view through the weatherstrip.

Like characters of reference designate like parts in all the figures.

It is understood that various changes in the form, proportion, size, shape, weight and other details of construction, within the scope of my invention may be resorted to without departing from the spirit or broad principle of my invention and without sacrificing any of the advantages thereof; and it is also understood that the drawings are to be interpreted as being illustrative and not restrictive.

A practical embodiment of the invention as illustrated in the drawings includes:

My weather strip is composed of two separate members A and B, A comprising a metallic member adapted to be attached to the door or swinging window; B being adapted to conjugately hinge on said member A, and depend therefrom. Both members A and B will hereinafter be more specifically described. Metal strip A is rigidly attached horizontally with nails, screws, or any usual means, adjacent the bottom edge of, and upon the outside face of, any inswinging door or casement window as shown at 1, said strip A extending across said door 1 adjacent its lower extremity from one edge to the other. A portion of said strip A lies flatly 2 against the outside surface of said door 1 from its upper edge tongued portion 3 to point 4. At point 4 it extends outwardly and downwardly to point 5; at point 5 it curves

inwardly toward door 1 and upwardly in a circular manner, as better seen in Figures 3 and 5, terminating at its free edge 6. It will be seen that said metal strip A between said points 5 and 6 does not form a complete loop. I provide a second metal strip B which is of the same length as strip A, and which has its upper edge 8 circularly curved to point 9 at the same radius of curve as described by said strip A between its points 5 and 6, being adapted to conjugately hinge thereto. Said curved portion of said strip B working within and in conjunction with the said circularly curved portion of said strip A, to form a weather-proof hinge. Said strip B extends laterally in a straight manner to point 10, where it forms a bulge 11 extending to point 12. At point 12 said metal strip B forms lip 13, after which it returns toward door 1 to a point forming a second and reversed lip 14 extending backwardly to tongued point 15 at the edge of the metal. Between reversed lip 14 and edge 15 of metal strip B is a plurality of holding points 16 and 17 which are pressed out of said metal strip B, to hold in place between the portion of member B extending between 14 and 15 and the portion of said member B extending between lips 13 and 14, a strip 18, which is made of felt or any suitable material. Felt strip 18 is of the same length as are metal strips A and B, and has one of its edges caught between the bends of said metal strip B, its other edge extending past the edge 15 and lip 13 of said metal strip B. Anchored within lip 13 and extending laterally to a point adjacent the end of lip 14 and anchored between the end of lip 14 and the portion between points 9 and 10 of said strip B, and extending longitudinally beneath bulge 11 to points adjacent each end of said metal strip B, is reinforcing-bar 19. Both ends of said strip B at point 9 and at lip 13 are split longitudinally for a distance great enough to allow the bending of the metal between said splits over the end of said reinforcing bar 19 as shown in Fig. 2 at point 20. Adjacent one corner of said door 1 and upon the latch side thereof I provide triangularly shaped spring housing 21 and retrieving spring 22, both of which are attached at their upper ends to door 1 by wood screw 23. Said spring 22 operates within and is housed by said housing 21. The lower end of housing 21 is fastened to door 1 by wood screws 24 and 25, its lower edge being adjacent point 4 on strip A. The lower end of said spring 22 forms a hook 26 which hooks through and anchors into aligned holes 27 provided therefor in strip B and reinforcing-bar 19 at a point adjacent the lower edge of said bulge 11. Positioned by wood screws 28 and 29 at a point on the latch side of the door or window casing 1 adjacent one corner thereof and in such a manner as to engage the upper side of strip B near one of its ends

I provide curved metal abutting plate 30, better seen in Figs. 1 and 3. I further provide at the opposite side of door 1 from abutting plate 30 and adjacent the lower corner of said door 1 metal angle plate 31. Angle plate 31 is attached rigidly to the door jamb 32 of the opening with a plurality of screws 33 and 34 in such a manner as to engage door 1 and fit closely against the corner thereof, thus sealing the crack between said door 1 and said jamb 32 and the bottom of said strip B. In the same relative position as is positioned holes 27 from the end of said strip B and the end of said bar 19, but through the opposite ends thereof, I provide holes 35, as may be better seen in Fig. 1. Said hole 35 is to be used when it is desirable to reverse the side of hanging of a door, or when it is desired to use two retrieving springs upon one door. The inventor does not wish to be bound as to the use of abutting plate 30, retrieving spring 22 and housing 21 only adjacent the latch edge of a door or window, as different doors may require the use of all of them adjacent either, or both edges. It is my intention to leave out of my device reinforcing-bar 19 except in cases of extremely wide openings where its use is necessary to eliminate the tendency of twisting. For use in connection with openings which have a door or swinging window hanging at each of its sides and swinging together in the middle, I provide abutting plate 36, better seen in Fig. 4. Said abutting plate 36 is positioned at the center of said opening and upon the threshold thereof with wood screws 37 and 38 in such a manner as to engage and close strip B when it is positioned on both of said doors or swinging windows.

It will be seen that the installation of my device is simple and does not require any grooving or the removal of the door or window. Metal strip A is merely attached to the door 1 in the specified position by use of wood screws. Hook 26 is then placed through holes 27. Spring 22 and housing 21 are then placed in specified position on door 1 by wood screws. Strip B is then pushed down by hand pressure until felt strip 18 is pressing tightly against the threshold or floor. Butting plate 30 is then attached by screws to the side of the door or window casing in such a position as to hold said strip 18 tightly against said floor. Angle plate 31 is then positioned with wood screws.

In operation, when door or swinging window is closed, the top surface of strip B below bulge 11, comes in contact with the lower edge of butting plate 30, which forces said strip B to travel circularly downward until felt strip 18 is tightly held against the floor. When door is opened, retrieving spring 22 pulls up on said strip B which, through the agency of the curved weather tight hinge formed at the circular meeting points of strips

A and B moves upward and clears said bottom of window casing, or threshold. It will further be seen that my device will not mar or deface the floor, floor covering, and the like, because only the said felt strip 18 comes 5 in contact with the mat any time. It will also be seen that felt strip 18 will prevent the entering of the elements, at the bottom of an opening, and that abutting plate 30 and angle plate 31 will close the cracks at the lower 10 corners of said openings.

In use with double doors, abutting plate 36 is used at the center of the opening. It is then necessary to install angle plate 31 in each corner of the opening, for closing the 15 corner cracks.

Obviously, the invention is susceptible of embodiment in forms other than that which is illustrated in the accompanying drawings and described herein, and applicable for the 20 uses and purposes other than as detailed, and I therefore consider as my own all such modifications and adaptations and other uses of the form of the device herein described as fairly fall within the scope of my invention.

Having thus described my invention what is claimed and desired to be secured by Letters Patent, is:

1. The combination with a weather strip having an upper strip member adapted to be attached to a door, and having a lower strip member hingedly engaging said upper strip member, of organization in which the lower member is formed to receive a bar, and whereby the bar is inserted within the lower member and retained therein by the turning down of the ends of said lower member.

2. The combination with a weather strip having an upper strip member adapted to be attached to a door, and having a lower strip member hingedly engaging said upper strip member and adapted to contact a floor, of a plate for closing space between the corner portions of the door and the corner portions of the door enclosure.

3. The combination with a weather strip having an upper strip member adapted to be attached to a door, and having a lower strip member hingedly engaging said upper strip member, of a reinforcing bar retained within 50 a bend of said lower strip member.

CHARLES F. MYERS.
